CLAIM

The ornamental design for a combined packing and carrying case, as shown and described.

DESCRIPTION

FIG. 1 is a back side perspective view of the combined packing and carrying case in accordance with of the present invention.

FIG. 2 is a front side view of the combined packing and carrying case depicted in FIG. 1;

FIG. 3 is a back side view of the combined packing and carrying case depicted in FIG. 1;

FIG. 4 is a left side view of the combined packing and carrying case depicted in FIG. 1;

FIG. 5 is a right side view of the combined packing and carrying case depicted in FIG. 1;

FIG. 6 is a top side view of the combined packing and carrying case depicted in FIG. 1;

FIG. 7 is a bottom side view of the combined packing and carrying case depicted in FIG. 1; and,

FIG. 8 is a front side perspective view of the combined packing and carrying case depicted in FIG. 1 shown in an open configuration.

The broken lines shown in the drawings illustrate portions of the combined packing and carrying case and form no part of the claimed design.

1 Claim, 7 Drawing Sheets
